UNITED STATES PATENT OFFICE

2,488,834

FLOOR SCRAPING AND SANDING MACHINE

James T. Simpson, deceased, late of Macon, Ga.,
by Madeline Simpson Williams, administratrix,
Macon, Ga.

Application February 6, 1948, Serial No. 6,718

3 Claims. (Cl. 51—176)

1

This invention relates to a floor scraping and sanding machine and has for an object thereof to provide an improved machine of this nature which can be used to both scrape and sand the floor simultaneously, and which can, by a simple adjustment, be used to sand a floor without scraping it, and without the necessity of removing the scraping blades.

A further object of this invention is to provide a combined sanding and scraping machine which will sand the floor area immediately after the scraping blade has passed thereover and before the next scraping action takes place, thereby tending to avoid the usual scraped or rasped floor surface provided by the conventional scrapers. In addition, when the floor surface has been scraped and sanded to the approximately finished surface, the same machine, by making a slight adjustment and without removing any parts, may be used for making a final light sanding action on the floor surface to provide the final finished smooth floor surface desired.

With the foregoing and other objects in view, as will hereinafter become apparent, this invention includes the combinations, construction and arrangement of parts hereinafter set forth, claimed, and illustrated on the accompanying drawings, wherein:

Fig. 1 is a front elevational view, partly in section of the floor scraping and sanding machine of this invention;

Fig. 2 is a side elevational view of Fig. 1;

Fig. 3 is an enlarged detailed view of the blade mounting, and

Fig. 4 is a perspective detail view of one blade.

There is shown at 10 the floor scraping and sanding machine of this invention including a framework or housing 11 mounted on wheels or rollers 12. Mounted on the housing 11 directly over the rear rollers 12 is an electric motor 14 controlled by a switch 15 conveniently mounted on a handle 16 secured at 17 to the rear end of the housing 11. A power wire 18 to the switch 15 may be attached to any suitable electric power source.

Mounted directly over the front rollers 12 is the operating drum 20, the drum 20 being provided with a shaft extending through its axis into journal supports 21. Extending into the top of each journal support 21 is a knob 22 connected by a reduced neck 23 to the bottom of a bolt 24 threaded through a nut 25 affixed to the housing 11 and terminating in knurled heads 26. At the outer side of one journal support 21 there is provided a projecting guide pin 27 which ex-

2

tends into a suitably formed vertical guide slot 28 in an upright 30 of the housing 11. At the other side, the drum shaft extends through a guide sleeve 31 and has a pulley 32 keyed thereon. 5 A power belt 33 connects the drum shaft pulley 32 to a pulley 34 keyed on the motor shaft 35 of the motor 14.

Secured to and spaced about the drum 20 by stud bolts 40 are four cellular rubber cushions 36 10 mounted on base plates 37. Sheets of sand paper 38 are detachably wrapped and secured about the cushions 36 by any suitable conventional means. As here shown, the base plates 37 secure the ends of the sand paper 38 against the 15 surface of the drum 20.

Between each pair of cushions 36 there is attached a blade support 41 to the drum 20. As shown, each blade support 41 consists of an angle bar of spring material having its leading edge 20 secured to the drum 20 by a stud bolt 43 while its after edge 44 is provided with circumferentially extending slots 45 through which stud bolts 46 are affixed to the drum 20. Secured to the blade supports 41 are the cutter blades 47 by 25 means of stud bolts 48. As shown in Fig. 4, each blade is provided with a series of $\frac{1}{2}$ " cutter edges 50 separated by $\frac{1}{2}$ " gaps 51 which are ground $\frac{1}{2}$ " deep. The edges 50 are sharpened to a chisel edge and then rolled or swaged to provide a hooked scraper edge pointing in the direction of rotation of the drum 20.

As shown, the cutting edges of one blade are offset from the cutting edges of the next blade. The two blades, not visible in Fig. 1, are each offset by one-quarter of a cutter edge width so that there is a complete overlapping of the cutting blades in one complete revolution of the drum 20. Instead of making the blades in a set of four, as just described, the blades could be made identical, and then mounted in offset relation to each other. As normally mounted, the edges of the blades 47 are one-quarter of an inch within the circumference of the surface of the sandpaper 38.

45 In operation, with the blades and the sandpaper properly mounted, the threaded shaft or bolt 24 is adjusted to lower the drum within the housing, thus causing the cushion 36 to compress until the blade edges 50 are the desired 50 amount below the bottom edge of the front rollers 12. The amount that the blade edge is below the roller determines the maximum cut that each blade can make. When the drum is rotating, each cut is followed by a sanding operation by the succeeding cushion and sandpaper; the drum

rotating counterclockwise as viewed in Fig. 1. Due to the position of the weighty motor 14 directly over the rear rollers 12, the operator can easily control the pressure on the drum 20 and the cutting edge 50 by means of the handle 16, by merely tilting the handle downward to lessen the pressure and upward to increase the pressure. When the floor surface has been scraped and sanded to approximately the desired condition, a final finish can be provided on the floor by then rotating the knurled boltheads 26 to raise the cutter edges 50 to slightly above the bottom edge of the front rollers 12, and then continuing the operation of the drum. In this position, the blades will no longer do any cutting action, but the sand paper will still sand and polish the floor with a light pressure to apply a final smooth finish.

While the device has been shown and the structure described in detail, it is obvious that this invention is not to be considered as being limited to the exact form disclosed, and that changes may be made therein within the scope of what is claimed, without departing from the spirit of the invention.

Having thus set forth and disclosed the nature of this invention, what is claimed is:

1. In a floor scraping and sanding machine, a drum, a plurality of scraping knives, means for adjustably and resiliently supporting said knives about said drum, said knife supporting means comprising resilient angle bar means, the leading edge of said bar means being secured to said drum, the leading angle face providing a knife supporting surface, the after edge of said angle bar means being provided with circumferentially extending slots and a stud bolt extending through each of said slots to said drum, each knife having a plurality of spaced apart serrated cutting edges thereon, the cutting edges of each knife being in staggered relationship to the cutting edges of at least one other of the knives, and a plurality of resilient sand paper supporting means, said scraping knives and said sand paper supporting means alternating about the periphery of said drum, the outer periphery of said sand paper supporting means being normally greater than the outer periphery of the knife cutting edges, and means for adjusting said drum in said machine to compress said resilient sand paper supporting means, as said drum rotates, to cause the periphery of said sand paper supporting means to coincide with the knife cutting edges' periphery, whereby both cutting and sanding may be performed in alternating sequence on a floor surface when the peripheries coincide, and sanding alone may be performed when the drum has been adjusted to permit the periphery of the sanding surface to remain substantially greater than that of the cutting edges.

2. In a floor scraping and sanding machine, a drum, a plurality of scraping knives, means for adjustably and resiliently supporting said knives about said drum, said knife supporting means comprising resilient angle bar means, the leading edge of said bar means being secured to said drum, the leading angle face providing a knife supporting surface, the after edge of said angle bar means being provided with circumferentially

extending slot means and a stud bolt extending through each of said slot means to said drum, and a plurality of resilient sandpaper supporting rubber cushion means, said scraping knives and said sandpaper supporting means alternating about the periphery of said drum, the outer periphery of said sand paper supporting means being normally greater than the outer periphery of the knife cutting edges, whereby sanding alone may be performed, and means for adjusting said drum in said machine to cause said peripheries to coincide on a floor surface to both cut and sand in alternating sequence.

3. In a floor scraping and sanding machine, a drum, a plurality of scraping knives, means for adjustably and resiliently supporting said knives about said drum, said knife supporting means comprising resilient angle bar means, the leading edge of said bar means being secured to said drum, the leading angle face providing a knife supporting surface, the after edge of said angle bar means being provided with circumferentially extending slots and a stud bolt extending through each of said slots to said drum, each knife having a plurality of spaced apart serrated cutting edges thereon, the cutting edges of each knife being in staggered relationship to the cutting edges of at least one other of the knives, and a plurality of resilient sandpaper supporting means, said scraping knives and said sandpaper supporting means alternating about the periphery of said drum, the outer periphery of said sand paper supporting means being normally greater than the outer periphery of the knife cutting edges, and means for adjusting said drum in said machine to compress said resilient sand paper supporting means, as said drum rotates, to cause the periphery of said sand paper supporting means to coincide with the knife cutting edges' periphery, whereby both cutting and sanding may be performed in alternating sequence on a floor surface when the peripheries coincide, and sanding alone may be performed when the drum has been adjusted to permit the periphery of the sanding surface to remain substantially greater than that of the cutting edges, the knife cutting edges being curved forwardly in the direction of rotation of said drum.

MADELINE SIMPSON WILLIAMS,
50 Administratrix of the Estate of James T. Simpson, Deceased.
